UNITED STATES PATENT OFFICE.

ANGELO PERRI, OF WATERTOWN, MASSACHUSETTS, ASSIGNOR TO REECE SHOE MACHINERY COMPANY, OF BOSTON, MASSACHUSETTS, A CORPORATION OF MAINE.

WIPING MECHANISM.

1,420,574.

Specification of Letters Patent. Patented June 20, 1922.

Application filed August 14, 1919. Serial No. 317,500.

To all whom it may concern:

Be it known that I, ANGELO PERRI, a citizen of the United States, residing at Watertown, in the county of Middlesex and State 5 of Massachusetts, have invented a new and useful Wiping Mechanism, of which the following is a specification, reference being had therein to the accompanying drawing.

This invention is a novel wiping mechanism. This application and patent is a companion case to my copending case entitled Shoe lasting machine, filed August 14, 1919, Serial No. 317,498. Said copending case discloses a complete machine embodying 15 pulling-over mechanism, toe wiping mechanism, heel wiping mechanism and a shoe holding device or jack shiftable so as to change the shoe position after the pulling-over to place it advantageously to co-operate with the wiping mechanisms. The present case has reference more particularly to the toe wiping mechanism, which is only generally indicated in said copending case. It is to be understood that, while the wiping 25 mechanism of the present case is designed and adapted more particularly to the wiping of toe ends of shoes, many features might be used in wiping mechanisms for the heel ends; also the mechanism hereof would be 30 useful, not merely in a complete pulling-over and wiping machine, as in said copending case, but also in other forms of lasting machines, for example, the well known bed laster, in which no pulling-over, but only 35 wiping, is performed; and the scope and utility of the present invention are not intended to be restricted in these respects.

The main object of the present invention is to afford a shoe wiping mechanism operating in a more efficient and convenient manner, and with better results in the product, as compared, for example, with the mechanism generally shown in my prior Patent No. 1,260,034, patented March 19, 1918. An- 45 other object is to afford an improved construction for readily bringing about the reversal of the contour of the wiping plates, so as to quickly readapt the machine for right and left shoes, respectively, this being 50 in a way an improvement over the mechanism shown in my prior Patent No. 1,260,033, patented March 19, 1918. Another object is to afford a superior means for symmetri-

cally shifting the wiping mechanism across the axis of the machine to bring it into 55 proper position for acting upon right and left shoes, respectively. A further object is to simplify and render more convenient the act of causing the reversals mentioned, preferably by providing a single lever or 60 control part, which, when operated, both shifts the wiping mechanism across the axis of the machine and reverses the contour of the wiping plates. Other and more particular objects and advantages of the present invention will be made clear in the hereinafter following description of an embodiment thereof, or will be apparent to those skilled in the art.

To the attainment of the above mentioned 70 objects, the present invention consists in the novel machine, mechanism, combinations, devices and arrangements herein illustrated, described or claimed.

In the accompanying drawings Fig. 1 is 75 a front elevation of a wiping mechanism designed more particularly for the toe end of shoes, and adapted, for example, for use in a lasting machine such as is illustrated in said copending case, wherein at the left side 80 of Fig. 1 will be seen the same mechanism as in Fig. 1 hereof, the same being shown in appropriate surroundings and with appropriate fittings and adjustments unnecessary to repeat in the present case. Indeed, for 85 convenience in the present case the wiping mechanism has been changed from the inclined position indicated in the copending case, and which it would possess in practice, to a horizontal position, to afford more 90 satisfactory illustration and explanation of the structure of the mechanism. It will be understood that the axis of the machine and shoe run generally from left to right in Fig. 1, the wiper plates being at the extreme 95 right of the figure, and advancing toward the shoe in a rightward direction.

Fig. 2 is a left elevation of the mechanism shown in Fig. 1.

Fig. 3 is a right elevation of the mechanism shown in Figs. 1 and 2.

Fig. 4 is a detail taken on the plane 4-4 of Fig. 3.

Fig. 5 is a top plan view of the wiping mechanism hereof.

Fig. 6 is a generally central vertical sec-

tion of the toe wiping mechanism hereof, the parts which are shown in elevation being seen in front view.

Fig. 7 is a top plan view of the actual 5 wiper plates and operating mechanism detached from the remainder of the machine and shown set for a right shoe.

Fig. 8 is a similar view with the parts re-adjusted or reversed to give the proper 10 contour for a left shoe.

Fig. 9 is a top plan view, partly in section, showing the mechanism for symmetrically shifting the wipers from front to rear to accommodate the same to a right or left 15 shoe, this figure showing the same in a central or neutral position.

Fig. 10 in top view shows the same parts as Fig. 9, but shifted into position for operation upon a left shoe.

20 I may conveniently first point out the wiper plates 17 at the extreme right and the actuating or wiping handle 18 at the extreme left. The plates and their fittings are mounted on a carrier or first carriage 20, 25 which is cylindrical and is slidably fitted within a second carriage or trunnioned shell 21. This is arranged to tilt longitudinally to give the adjustment in that respect to the wiping plates, and is fulcrumed upon 30 the succeeding carriage 22, which is of a rotary nature for the purpose of altering the direction of wiping action in reversing the machine for right and left shoes. The base of the rotating carriage 22 rests flatly 35 upon the top surface of a transversely swinging carriage 23, the shifting of which also takes part in reversing the machine for right and left shoes. The carriage 23 is pivoted at its left end to a transversely sliding carriage 24 beneath it, this in turn being dovetailed at the top of what may be 40 termed the base carriage 25.

The fittings below this point are not herein shown and per se form no part of the 45 present invention, but can be ascertained from Fig. 1 of said copending case, where it will be seen that the base carriage 25 is mounted to slide vertically on an upstanding post, fulcrumed at the base of the machine. A 50 wiping pedal is provided, so that during the wiping action the operator can lift and lower the entire wiping head, as is required, this being necessary to be done in conjunction with the actual wiping movements effected by the handle 18 before mentioned. Also the upright post which supports the 55 base carriage is capable of bodily swinging toward and from the shoe, so as to carry the wiping mechanism conveniently into and 60 from operative position, and when advanced and set in operative position the post is further adjustable toward and from the shoe as desired, by a screw adjusting device shown in the copending case. These parts 65 omitted herefrom are substantially also dis-

closed at the lower left side of Fig. 1 of my prior Patent No. 1,260,034.

The dovetail connection of transversely sliding carriage 24 upon the base carriage is well shown in Figs. 1 and 6. This sliding takes place upon the reversal of the machine for rights and lefts. Stops are provided to limit the extent of sliding. For example, at the front side a stop screw 27 is shown, rotatively secured to sliding carriage 24. Beneath it a bracket 26 stands out forwardly from carriage 25. Symmetrical stops 28, 28 are shifted together or apart by the right and left threads of screw 27. Upstanding from the bracket is a block or 80 central stop 29, between the stops 28 and through which screw 27 loosely passes. When the carriage 24 is slid back or front from the neutral position shown, one or the other of stops 28 contacts stop 29 and determines the position of the carriage.

The carriage 23 will be thrown across the machine and back by the reversing handle 40, afterwards to be described.

The transversely swinging carriage 23 is 90 fulcrumed at 30 to the carriage 24, so that the free or right end of the carriage 23 may swing rearwardly and forwardly. The rotary carriage 22 in turn is centrally fulcrumed at the right or free end of swinging carriage 23. The following contrivance is employed to automatically rotate the carriage 22 when the carriage 23 is swung across the machine. Carriage 22, which is disc-like, is provided with a curved rack 31, engaging the large-radius portion 32 of a toothed member mounted on the carriage 23, the small-radius portion 33 of which in turn engages a pinion 34 mounted on the stud 30 before mentioned, at the upper side of the carriage 23. The pinion 34 is held against free rotation, either by being fast on the stud 30, or in the alternative manner which will be described. By this arrangement, when the carriage 23 is swung the toothed member travels around the pinion causing its rotation and in turn the rotation of the carriage 22. It may be desired to rotate the carriage 22 to a greater extent in order to secure the desired angle of 100 wiping action. To this end, the pinion 34 is rotatable by the following means. It is shown meshing with a pair of sliding racks 35 guided in portions of the carriage 23 and having downward studs or offsets at their 110 right ends adapted to engage with cams 36 mounted upon the underlying carriage 24. By this, when the carriage 23 is swung one or the other of the cams 36, acting on its rack 35, will slightly shift the rack causing 120 rotation of the pinion 34 and increased rotation of carriage 22. The described parts, on carriage 23, will be covered over for protection, the cover being omitted in Figs. 9 and 10 but shown in Figs. 1, 2, 5 and 6. 130

At the right hand edge of the sliding carriage 24 is an upstanding flange or rim 37, concentric with the pivot about which the carriage 23 swings, and attached on top of this rim is a hold-down or bearing plate 38, extending over and securely holding in position the rim of the rotary carriage 22, as clearly seen in Fig. 6. The top side of the flat concentric hold-down plate 38 serves also as a sliding surface or bearing for certain parts to be described, which run along its top.

By reason of the described fittings and arrangements of the sliding carriage 24, swinging carriage 23 and the rotary carriage 22, all three of them may be shifted to effect the reversal of the machine for right and left shoes alternately in a single action or movement. A single large upright reversing handle 40 is shown in Figs. 1, 2; 3 and 5, this standing at the rear, but in easy access to the operator. This handle is so connected as to perform several functions, namely, first to unlock and reverse the contour of the wiping plates themselves, all of which will be later described, and thereupon to effect the described reversals of the three carriages 24, 23, 22, which action will now be described. Referring to Fig. 3, a link 41 is shown, extending forwardly from the reversing lever. This is slotted at 42, giving a certain amount of idle motion or play of the lever before the reversing takes place. This is to give time for the lever to preliminarily unlock, reverse and relock the wiper plates themselves. When the stud has traversed the slot 42 in the link 41, the continued forward movement of the lever 40 causes the link to throw forwardly a second lever 43, which at its top end has a swivel connection 44, from which extends a link 45 to a swivel connection 46, at the top of a block 47, having fixed relation to the swinging carriage 23, and sliding around upon the top side of the concentric bearing plate 38 before mentioned.

The mode of connection of the block 47 to the swinging carriage will now be described. A threaded rod 48 loosely rotates within the bearing in the block 47, but is prevented by a pin and slot, as seen in Fig. 6, from endwise play. The threaded rod or screw shaft 48 has righthand threads at its rear and lefthand threads at its front part, and beyond these threads the rod is journaled in bearings or brackets 49, extending upwardly and rightwardly from the swinging carriage. Upon a forward extension of the rod is a hand wheel 50, by which the rod may be turned for symmetrically adjusting toward and from each other a pair of blocks 51, 51, engaged on the rod at either side of the central block 47. These blocks constitute stops or positioning members for determining the forward and rearward throw of the swing-

ing carriage. Each of the blocks 51, and also the block 47, is provided with an underneath recess 53. It will be understood that the threaded rod and the entire system of blocks carried thereby shifts rearwardly and forwardly with the swinging carriage. In the figures these are shown in a central or neutral position where they are held by a pin 54, centrally mounted within a barrel 55 on the underneath carriage 24. The pin is pressed upwardly by a spring 56, as seen in Fig. 6, and is shown engaged in the recess 53 at the underside of the central block 47. The pin may be disengaged or depressed by lifting the hand lever 57, thus unlocking the system of parts which position the swinging carriage.

Assuming, now, that a right shoe has been lasted, and a left shoe is about to be lasted, and the reversing lever 40 has been thrown about halfway to the rear, the parts are shown in the position they would occupy if the operator stopped the rearward throw of the handle, so as to allow the stop pin to engage in the recess beneath the central block 47. The pin is shown so engaged. If the handle 57 is raised to release the pin, a continued rearward movement of the reversing handle will act through link 41, lever 43 and link 45 to pull rearwardly the block 47, and with it the threaded rod 48 and the parts associated therewith. The swing of the carriage 23 will cease when the block 51 comes directly over the stop pin 54, as the pin will then snap up into the recess 53, thus locking the swinging carriage in its rearward position.

As before stated, the rotary carriage 22 has upstanding bracket portions, at the top of which is trunnioned the hollow shell or tilting carriage 21. For the purpose of adjusting the longitudinal tilt, the adjusting wheel 60 is shown, the hub of this having a threaded recess with right and left threads engaging corresponding screws connected respectively to the carriage 22 and the carriage 21.

The lateral tilt may be effected by the following. By means of a key 62, a lateral tilting handle 63 is slidably engaged with the cylindrical carriage 20 within the hollow shell 21, see Fig. 6. The hub portion of the handle surrounds the carriage and extends upwardly within convenient reach. A latch lever 64 holds it in desired adjustment, but by pressing this lever, the tilting lever 63 may be thrown forwardly or rearwardly. When set and released a spring-pressed half-nut 65 is brought into engagement with a threaded rod 66, having a hand wheel 67 at its forward end, so that by turning the hand wheel a finer adjustment of tilt may be effected, after the tilt has been approximately attained by the handle 63. The rod 66 engages the half-nut in its threaded

portion, while its far end is swivelled on an upstanding projection 68, as seen in Figs. 2 and 5.

The wiper handle 18 is connected to the wiper carrier 20 as follows. The handle is directly pivoted to a link 70 at the rear, see Fig. 5, this link being pivoted on a projection on the hollow shell 21. The handle has a swivel connection 71 with the rear end 10 of the wiper carrier 20. Thereby throwing the handle 18 to right or left advances or retracts the carrier or wiper plates. When the wiping plates have been advanced and the wiping is completed, the parts may be 15 locked in such position by means of toothed rack 72, mounted on the hollow shell 21 and engaged by the extremity of a latch lever 73, pivoted upon the main wiping lever 18. Depressing the latch lever frees the wiping 20 lever for action.

The wiper plates are mounted to the right of the wiper carrier 20. Each wiper plate is reversible in position and has two contours, one for right shoes, one for left shoes. Thus, 25 in Fig. 7, the plates are shown set for a right shoe, the rear plate having a contour 83 contiguous to the contour 84 of the front plate. Each of the plates reverses preferably by rotation in a horizontal plane about 30 an axis within the body of the plate, and at the opposite side to the right shoe contour each plate has a left shoe contour 81 and 82, respectively, which in Fig. 8 are shown matched up ready for operation on left 35 shoes. I will first describe the action and mechanism for giving wiping movements to the plate, and afterwards the means for reversing them for right and left shoes. Each plate is mounted at its pivot or center 85, 40 above an arc-shaped block or segment 86, having a dove-tail connection 87 upon the enlarged extension or head 88 of the carrier 20. The segments 86 are really curved slides capable of being moved toward and from the 45 shoe by a curved motion about a center substantially at the center of the apex of the shoe toe. The contiguous corners of the two wiper plates meet at its center or apex, and therefore the wiping movements of the 50 plates take place without at any time breaking the continuity of the wiping edge.

For causing the wiping movements of the plates, each sliding segment 86 is provided with a toothed rack 90 engaged by a pinion 55 91 mounted loosely on a stud upstanding from the carrier head 88. Attached to each pinion 91 is a lower and smaller pinion 92, engaged by a longitudinal toothed rack 93, secured against movement with the carrier, 60 by being mounted on a vertical rod 94. These parts are shown in Fig. 7, and in Fig. 1 the vertical rod is shown as engaged in a vertical guide sleeve 95. The two guide sleeves 95 at the front and rear are both secured on a supporting ring 96, surrounding

a portion of the shell 21 and capable of rotating thereon to accommodate itself to the tilt of the wiping mechanism, but incapable of longitudinal motion with the wiper carrier.

The result of the described connections is that, when the wiper carrier 20 is thrust forwardly relatively to the shell and the vertical rods 94, the racks 93, remaining stationary, cause the rotation of the pinions 92 75 and 91, and thereby the concentric swinging apart of the segment slides 86 and swinging together of the wiper plates.

When in either position, namely, for right shoe or left shoe, the wiper plates are locked, 80 as shown in Figs. 7 and 8, by lock pins 99, spring-pressed upwardly into circular recesses at diametrical points on each plate. Before the plates can be reversed, the locking pins must be depressed, and I prefer to 85 do this automatically. An unlocking lever 100, best shown in Fig. 1, is pivoted to the carrier head. It has its right extremity in engagement with the locking pins. It is understood that there is an unlocking lever 90 at each side. The vertical rods 94, previously mentioned, are provided with pins 101, engaging the yoke left ends of the unlocking levers. By this arrangement the up-pulling of the pins 94 will unlock the wiper plates 95 to permit their reversal. This does not affect the function of the rods 94, as holders for the racks 92 before mentioned, as the rods slide freely vertically through the racks. In order to simultaneously lift both of the 100 rods 94, I provide a reverser slide 103, mounted to be movable to right and left on top of the shell 21 by means of guides 104 on the latter. The reverser slide is slotted at 105 to accommodate a stop pin 106, which 105 limits its advancing and retracting movement. The slide is movable directly beneath the cross rod 107, which extends from side to side and connects the upper ends of the two vertical rods 94. The slide, in order to 110 lift the cross rod and the vertical rods to unlock the wipers, is provided with a cam, comprising, first, the up-slanting surface 108, followed by the dwell or horizontal surface 109, and then a down slant 110. In Fig. 1 115 the slide 103 is moved slightly to the left, the rod 107 is lifted to the dwell 109, and thus unlocks the wiper plates, which may then be reversed, after which the continued leftward movement of the slide would let the 120 rod 107 ride down the incline 110 to relock the plates. I prefer that the same member or slide 103, which thus unlocks and relocks the plates, shall also reverse them for right and left shoes. For this purpose the extreme right end of the reverser slide has a pair of downward arms 111 at front and rear. The lower parts of these arms have outward flanges, 112 at the right, 113 at the left. It will be understood that this entire 130

system is moved to right and left from the reversing slide. Figs. 7 and 8 show the relative position of the depending arms 111 and the reversing mechanism. Between the 5 flanges 112 and 113 engages the hooked end of a small lever 115, mounted on a sliding rack 116, which in turn is mounted on the segment 86 which carries the wiper plates. The rack is in engagement with a pinion 117, 10 which in turn engages a pinion 118, concentric with the before mentioned pivot 85 of each wiper plate. The wiper plate is laid detachably upon its pivot 85 and is compelled to rotate with the pinion 118 by a pair 15 of little upstanding pins 119 at either side of the pivot 85.

It is now obvious that, if the reverser slide and the flanged arms 111 be retracted from the Fig. 7 position to the Fig. 8 position, this 20 will retract the rack 116 and rotate the pinion to swing the two wiper plates through a half rotation from the Fig. 7 to the Fig. 8 position. The reverser slide, therefore, when thrust to the left, first unlocks the wiper 25 plates, then reverses them, and then locks them. The hooked lever 115 rides idly between the flanges 112, 113, during the locking and unlocking, and the reversing is performed while the dwell portion 109 of the 30 reverser cam is in effect.

The wiper plates are shown uncovered in Figs. 7 and 8, but in practice they are covered, for example, by the pivoted cover plate 120, which may be swung up for interchanging the plates, but when swung down is secured in position by a screw device 121.

It has been before stated that I prefer to unlock and reverse the wiper plates in the same action or by the same part as the reversal of the carriages 24, 23 and 22 in changing the machine for right and left shoes alternately. Therefore I will now describe connections from the reversing lever 40 to the reverser slide 103. Engaging an 45 upstanding stud on the reverser slide is a rock arm 122, see Fig. 5. This is connected at the upper end of a rock shaft 123. This rock shaft is sectional, having a universal joint 124, sufficiently indicated in Figs. 1 and 6, and at its lower end the rock shaft has a rock arm 125, from which extends rearwardly a link 126 to a floating arm 127, pivoted at one side of the reversing lever 40. This permits a yielding connection between 50 the reversing lever and the reverser slide. The upper end of the arm 127 is yoked at 128, and springs 129, extending across the yoke, engage a block 130, mounted on the lever 40.

60 The result of these control connections is that, when the reversing lever 40 is thrown, it first acts to shift the reverser slide, and thereby unlock and reverse the wiper plates. The springs 129 are quite strong and do not 65 yield materially. During this action the

slot 42 prevents reversing movement of the carriages. After the wiper plates have been reversed, as described, the reversing lever takes effect to reverse the carriages, and during this motion the springs 129 yield 70 sufficiently to avoid obstructing the proper swing of the reversing lever.

A convenient device to present wire to the shoe for securing the wiped edges before the removal of the shoe may be as follows. 75 Figure 6 shows a bracket 135 extending downwardly from a portion of the wiper carrier 20. Pivoted to the bracket is a lever 136 which extends upwardly and is constantly pulled to the left by a spring 137 so 80 that it normally stands as shown, contacting with a stop lug 138. The lever 136 is forked, presenting two upwardly extending arms. At the top of each arm is a groove 139 through which the wire is fed from a 85 suitable supply. A spring retaining device 140 normally maintains the free end of the wire in the groove 139. The wire is thus always in the most convenient place for access and application to the shoe. The retaining spring by its yielding permits the securing wire to be drawn out from the groove when desired and replaced when the wiping has been completed and the wiped edges secured. The spring 137 yields per- 95 mitting the entire device to be swung toward the shoe as the securing wire is laid around the toe end.

It will thus be seen that I have described a wiping mechanism embodying the principles and attaining the advantages of the present invention. Since many features of design, arrangement, combination and detail may be variously modified without departing from the novel principles involved, 100 no limitation to such features is intended except in so far as specified in the appended 105 claims.

What is claimed is:

1. In a lasting machine for alternately 110 wiping right and left shoes, a wiping mechanism, a carriage therefor rectilinearly slideable freely and symmetrically across the center line of the machine to reverse the wiping mechanism for right and left shoes 115 and symmetrically acting stops limiting the reverse shifting of the carriage.

2. Lasting machine as in claim 1 and wherein is a means for oppositely and simultaneously adjusting both stops to alter the 120 effective opposite positions of the carriage.

3. In a lasting machine for alternately wiping right and left shoes, a wiping mechanism, a carriage therefor freely shiftable across the machine center line, and means 125 for determining its opposite positions comprising a non-central stop member (29), and a device carrying two members (28, 28) between which the stop member plays, substantially as shown and described. 130

4. In a lasting machine for alternately wiping right and left shoes, a wiping mechanism, a carriage swingable bodily and quickly across the center line of the machine for reversing it for right and left shoes, a pair of symmetrically opposite stops (51, 51) carried on said carriage, a device (48) for simultaneously symmetrically adjusting said stops, and a cooperating lock device (54) for locking the carriage in its opposite positions.
5. A wiping mechanism having a laterally tilting carriage, a reverser for throwing the carriage approximately to its opposite tilts for right and left shoes, a single locking device for locking the carriage in both of its reversed positions, and an adjusting screw operable in both reversed positions for independently finely adjusting the tilt at each position.
6. A wiping mechanism having a plurality of plates conforming to the contour to be wiped, one of said plates being reversible by rotation about an interior axis to the extent of substantially two right angles, such plate having substantially opposite contour portions corresponding to right and left shoes, respectively.
7. A wiping mechanism as in claim 6 and wherein both of two adjacent plates are reversed in position by rotation about interior axes.
8. A wiping mechanism as in claim 6, and wherein means are provided for rotating said reversible plate through substantially two right angles.
9. A wiping mechanism having rotatable plates reversible for changing the contour for right or left shoes, means for locking the plates in the two positions, and a single reversing member having connections for first unlocking, and then reversing the plates.
10. A wiping mechanism as in claim 9, and wherein the reversing member comprises a three-part cam, the first part unlocking the plates before the reversal and the third part permitting the relocking after the reversal.
11. A wiping mechanism having a wiper plate carrier, wiper plates thereon, said plates being movably reversible for right and left shoes, means for locking the plates in reversed positions, a shifting carriage for reversing the wiping mechanism for right and left shoe, and a single reverser for effecting the reversings mentioned.
12. A wiping mechanism as in claim 11, and wherein the reverser has connections for first unlocking then reversing the plates and then reversing the carriage.
13. In a lasting machine, a wiping mechanism reversible in contour, a carriage slideable across the center line of the machine, a carriage swingable across said slideable carriage, a carriage rotatable on said swingable carriage, and a single means for effecting said carriage movements to reverse the machine for right and left shoes and for reversing the contour.
14. In a lasting machine, a wiping mechanism reversible in contour, a carriage slideable across the center line of the machine, and a carriage swingable across said slideable carriage, and a single means for effecting said carriage movements to reverse the machine for right and left shoes and for reversing the contour.
15. In a lasting machine, a wiping mechanism reversible in contour, a carriage slideable across the center line of the machine, a carriage rotatable on said swingable carriage, and a single means for effecting said carriage movements to reverse the machine for right and left shoes and for reversing the contour.
16. In a lasting machine, a wiping mechanism reversible in contour, a carriage slideable across the center line of the machine, a carriage swingable across said slideable carriage, and a single means for effecting said carriage movements to reverse the machine for right and left shoes, consisting of a lever connected to said swinging carriage and for reversing the contour.
17. In a lasting machine for wiping right and left shoes alternately, a wiping mechanism, a carriage supporting the wiping mechanism and shiftable bodily across the machine for reversing the location of said wiping mechanism for right and left shoes, said wiping mechanism comprising wiping plates each having different contours for right and left shoes respectively and each plate reversible in position to present its different contours, a reverser, and connections from the reverser to said carriage and said mechanism such that the actuation of the reverser reverses both the location of the wiping mechanism and the position of the wiping plates thereof, whereby to effect quick reversal of the machine for wiping right and left shoes alternately.
18. In a lasting machine for wiping right and left shoes alternately, a wiping mechanism, a carriage supporting the wiping mechanism and shiftable across the machine for reversing the location of said wiping mechanism for right and left shoes, said wiping mechanism comprising wiping plates each reversible in position for right and left shoes, a reverser, and connections from the reverser to said carriage and said mechanism such that the actuation of the reverser reverses both the location of the wiping mechanism and the position of the wiping plates thereof.
19. A lasting machine as in claim 18 and wherein a rotatable carriage is interposed between the shiftable carriage and the wiping mechanism, and means actuated by said

reverser for rotating said rotatable carriage to symmetrically reverse the angle of action of the wiping mechanism.

20. In a lasting machine for wiping right and left shoes alternately, a wiping mechanism, a carriage supporting the wiping mechanism and slidable rectilinearly across the center line of the machine, said wiping mechanism comprising wiping plates reversible in position for right and left shoes, a reverser, and connections from the reverser to said carriage and said mechanism such that the actuation of the reverser reverses both the location of the wiping mechanism and the position of the wiping plates thereof.

21. A lasting machine as in claim 20 and wherein a swingable carriage is interposed between the slidable carriage and the wiping mechanism, and the connections from said reverser being such that its actuation reverses both carriages and the wiping mechanism.

22. Machine as in claim 18, and wherein the shiftable carriage is pivoted so as to shift bodily across the machine with a swinging movement, the reverser connected therewith for swinging the carriage across and with the wiping mechanism for reversing the position of the plates, for reversing the machine for right and left shoes.

23. Machine as in claim 18, and wherein a rotatable carriage is fulcrumed on said shiftable carriage and interposed between it and

the wiping mechanism, and the connections from the reverser being such as to reverse both carriages and the wiping mechanism.

24. In a lasting machine for wiping right and left shoes alternately, a wiping mechanism, a carriage rectilinearly shiftable across the center line of the machine, a carriage supported by said shiftable carriage and swingable laterally across the same, a carriage rotatably mounted on said swingable carriage and supporting the wiping mechanism, said wiping mechanism comprising wiping plates reversible in position to present different contours for right and left shoes, a reverser, and connections between the reverser and said carriages and wiping mechanism such that the actuation of the reverser reverses all said carriages and said wiping mechanism.

25. In a lasting machine for wiping right and left shoes alternately, a wiping mechanism bodily shiftable symmetrically to present it to right and left shoes, said wiping mechanism comprising wiping plates reversible in position to present different contours for right and left shoes, a reverser, and connections between the reverser and said mechanism such that the actuation of the reverser both bodily shifts the mechanism and reverses the position of the wiping plates thereof.

In testimony whereof, I have affixed my signature hereto.

ANGELO PERRI.
